UNITED STATES PATENT OFFICE

167,481

ERASURE SHIELD

Adolph Paul Osius, Detroit, Mich., assignor to Detroit Stamping Company, Detroit, Mich., a corporation of Michigan

Application September 25, 1951, Serial No. 16,733

Term of patent 7 years

(Cl. D74—1)

To all whom it may concern:

Be it known that I, Adolph Paul Osius, a citizen of the United States, residing at 4584 Pacific Avenue, Detroit, in the county of Wayne, State of Michigan, have invented a new, original, and ornamental Design for an Erasure Shield, of which the following is a specification, reference being had to the accompanying drawing, forming a part hereof.

Fig. 1 is a plan view of the shield;
Fig. 2 is a side elevation of the shield; and
Fig. 3 is a sectional view taken along the line 3—3 of Fig. 1.

I claim:

The ornamental design for an erasure shield, as shown.

A. PAUL OSIUS.
